HARRY H. GLIDDEN AND ELON P. HOUSE, OF SPRINGFIELD, ILLINOIS.

Design No. 3,370, dated February 16, 1869.

DESIGN FOR A TRADE-MARK

The Schedule referred to in these Letters Patent and making part of the same.

To whom it may concern:

Be it known that we, HARRY H. GLIDDEN and ELON P. HOUSE, of the city of Springfield, county of Sangamon, and State of Illinois, have originated a new Design for a Trade-Mark, of which the following is a full, clear, and exact description, reference being had to the accompanying drawings; making part of this specification.

Our design consists in connecting two large Q's together by a scroll, and inserting in the scroll the two words "Quit Quick," as is shown in the accompanying drawing.

This design can either be printed or lithographed,

and pasted upon the bottle containing the manufactured article, or it can be blown in the glass.

What we claim as our invention, and desire to secure by Letters Patent, is—

The combination and arrangement of two large Q's, connected together by a scroll, in which are inserted the words "Quit Quick," substantially as set forth, as a design for a trade-mark.

H. H. GLIDDEN.
E. P. HOUSE.
